Primary Examiner—Louis S. Zarfas*Assistant Examiner*—G. Andoll*Attorney, Agent, or Firm*—Gottlieb, Rackman & Reisman, P.C.[57] **CLAIM**

The ornamental design for a pet insecticide collar with surface ornamentation, as shown and described.

DESCRIPTION

FIG. 1 is an isometric perspective view of the pet insecticide collar with surface ornamentation showing my new design; FIG. 2 is an enlarged top plan view thereof in the open position;

FIG. 3 is a front view thereof;

FIG. 4 is a rear view thereof;

FIG. 5 is a left end view thereof;

FIG. 6 is a right end view thereof; and,

FIG. 7 is a bottom view thereof.

The broken line showing of the animal in FIG. 1 is for illustrative purposes only and forms no part of the claimed design.

The broken away showing of the claim in FIG. 2, 3, 4 and 7 is for ease of illustration.
